UNITED STATES PATENT OFFICE.

AUGUSTUS M. SOSA, OF CINCINNATI, OHIO, ASSIGNOR TO THE AMERICAN TOOL WORKS COMPANY, OF CINCINNATI, OHIO, A CORPORATION OF OHIO.

FEEDING MECHANISM FOR METAL-WORKING MACHINERY.

Application filed July 21, 1924. Serial No. 727,104.

My invention relates to feeding mechanism for metal working machinery, and is exemplified as applied for feeding the saddle of a so-called metal shaper, for presenting the work in successive or intermittent steps to the action of the tool, which is instanced as mounted on a reciprocating ram.

In machinery of this character, it is usual to mount the work upon a saddle which is feedable crosswise of the vertical plane in which the tool reciprocates, the saddle being slidable upon a rail, which is adjustable up and down with relation to the path of the tool. It is usual also to initiate the feeding movements from a fixed point of the machine, for instance, from the axis of rotation of the bull-wheel.

The point for application of the feeding movements is therefore stationarily positioned, and the point for reception of the feeding movements at the feeding device is adjustable vertically in a right line, resulting in different distances between said points at different elevations of the rail. It is one of the objects of the invention to compensate for the variant distances between these two points.

It is the object of the present invention, further, to provide novel means whereby to automatically maintain the means for applying the feeding movements, the means for receiving the feeding movements, and the connecting means therebetween, at substantial distance and angular relations to each other.

A further object is to provide novel means in the train of mechanism for accomplishing the feeding movements, whereby to permit yield due to the variant distances between points in the power applying mechanism and the power receiving mechanism during adjustments to elevation of the power receiving mechanism; and, further, to provide novel means whereby to automatically return the yielding member of said mechanism to normal relation.

A further object of the invention is to provide novel safety means whereby yield is permitted in the feeding train to compensate for obstruction to feeding movement of the element being fed, for instance,

when the saddle reaches the end of its feeding path; and, further, to provide novel gauging means for the adjustments of lengths of feeding movements. 55

The invention will be further readily understood from the following description and claims, and from the drawings, in which latter:

Fig. 1 is a side elevation of a shaping machine, partly broken away, and embodying my invention. 60

Fig. 2 is a plan view of my invention, partly in horizontal section on the irregular line 2—2 of Fig. 1. 65

Fig. 3 is a vertical cross-section of the clutch, taken on the line 3—3 of Fig. 2.

Fig. 4 is a diagrammatic view of the gearing for the same.

Fig. 5 is a vertical section of the feed-gearing, taken on the line 5—5 of Fig. 1. 70

Fig. 6 is a vertical cross-section of the same, taken in the plane of the line 6—6 of Fig. 5. 75

Fig. 7 is a front view detail of the ratchet mechanism, with the gear-casing shown in vertical section on the line 7—7 of Fig. 6.

Fig. 8 is a detail of the gauging mechanism, shown in horizontal section on the line 8—8 of Fig. 1. 80

Fig. 9 is a vertical section of the feed actuating mechanism, taken on the line 9—9 of Fig. 1.

Fig. 10 is a bottom view of the same.

Fig. 11 is a vertical section of the same, taken in the plane of the line 11—11 of Fig. 9. 85

Fig. 12 is a vertical section of the same, taken in the plane of the line 12—12 of Fig. 9. 90

Fig. 13 is a horizontal section of the same, taken in the plane of the line 13—13 of Fig. 12.

Fig. 14 is a horizontal section of a detail of the same, taken in the plane of the line 14—14 of Fig. 9; and, 95

Fig. 15 is a horizontal sectional detail of the clutch shifting mechanism, taken on the line 15—15 of Fig. 5. 100

The shaping machine exemplified comprises a usual frame 21, on which there is an upper guideway 22. A tool-ram 23 is re-

ciprocated lengthwise in the guideway, and has thereon a usual tool-holder 24, in which there is a tool 25.

The ram is arranged to be reciprocated by means of a usual rocker-arm 26, pivoted at its lower end on a shaft 27, and at its upper end articulated with a nut-block 28 by means of a link 29, the ram being adjustable in usual manner with relation to the nut-block for positioning the path of stroke of the tool.

The work is arranged to be supported on a usual work-table 31, suitably secured to a saddle 32, adjustable crosswise of the tool on a rail 33, along guideways 34, 35. This lateral adjustment of the saddle is effected by means of a feed-screw 36, which is threaded to a usual nut 37 on the saddle, the feed-screw being journaled in suitable bearings on the rail, one of which is shown at 38.

The rail is adjustable up and down on the frame, on guideways 41 on the frame, toward and from the path of reciprocation of the tool-ram, the adjustment being effected by means of a usual nut, journaled and held endwise on the rail, and manually or otherwise rotated in usual manner, and threaded about a screw 42 supported in endwise relation on the base 43 of the machine.

The feeding movements of the saddle are effected in synchronism with the reciprocating movements of the ram, taking place usually during the idle or return strokes of the ram. It is desirable, therefore, and usual to have the same point for power application for the feeding movements and for the reciprocations of the ram, instanced as the bull-wheel 45, the axis of rotation of which may be instanced as the fixed point for power application for the ram and for the feeding train.

The bull-wheel has a hub 47, in which there is a usual cross-guide 48, in which a block 49 is arranged to be adjusted by a feed-screw 50, having a bevel-pinion 51 fixed thereto, which is meshed by a bevel-gear 52 on a shaft 53, having an adjusting handle 54 at its outer end. (See Figs. 2, 9 and 10).

The block 49 has a usual crank-pin 58 thereon, surrounded by a usual slide-block 59, reciprocating in a guideway 60, on the rocker-arm 26, for translating the planetary movements of the crank-pin into the usual rocking movements of the arm 26 for reciprocating the ram. (See Figs. 1 and 2).

The hub of the bull-wheel is provided with an extension 63, in which there is a bushing 64, which is fixed to the bull-wheel so as to rotate therewith by a screw 65.

An eccentric block 67 is fixed to this bushing, as by a key 68 and a positioning screw 69. The eccentric block has an eccentric 70 thereon, which is journaled in a slide-block 71, having reciprocation in a

slideway 72 of a lever 73, shown as a rocker-arm. (See Figs. 9 and 11).

The hub of the bull-wheel is provided with a journal-sleeve 75, rotatable in a bearing 76 of the frame of the machine. 70

A journal-stud 79 is fixed to this bearing by screws 80, the journal having an annular flange 81 through which the screws are received. The flange spans the outer end of the hub of the bull-wheel. 75

A housing 83 comprises an inner section 84 and an outer section 85, connected by screws 86. It has a bearing 91 about the journal-stud 79 and a bearing 92 about a bushing 93 in which the shaft 53 is journaled. (See Figs. 2 and 9).

An arm 95 has a bearing 96 about an inner journal 97 of the housing, and constitutes a lever. This lever has a normal position with relation to the housing, which normal position is preferably a central position parallel with the normal position of the lever 73. 85

In order to maintain such relative normal position between the lever 95 and the housing, but to permit yield therebetween upon application of undue strain between the parts, I provide means whereby such yielding is permitted, (see Figs. 9, 12 and 13), exemplified as a spring 101, the ends of which are received in thimbles 102, 103, provided with enlargements forming annular shoulders 104, 105, the enlargements having endwise movements in a bore 106 of said lever. Collars 107, 108, are fixed to the sides 109 of said lever, as by screws 109, and form coacting shoulders for the shoulders 104, 105. 95

The spring and thimbles are preferably assembled by means of a shank comprising 105 the sections 111, 112, having threaded connection 113 between the same for connecting the same, and provided with heads 114, 115, arranged to abut the side walls 116, 117, of said housing. The heads are 110 provided with flat sides 118 for turning the shank-sections. (See Figs. 9, 12 and 13.)

When an undue lateral strain is applied to said lever in one direction, one of said thimbles will yield for compressing said 115 spring, and for returning the lever to normal relation, and when said lever has undue strain applied thereto in the opposite direction, the other of said thimbles will yield, causing compression of the spring, the 120 spring returning the parts to normal relation when said undue pressure has ceased.

Similar relative yielding movements take place when the undue strain is applied to the housing, in which case one or the other 125 of said walls 116, 117, causes compression of said spring in one or the opposite direction, the spring returning the parts to normal relations when such undue strain has been removed. 139

The lever 73 has an adjusting screw 121 journaled therein in bearings 122, 123, (see Figs. 9 and 11), the bearing 122 being in a cross-piece 124 fixed to the body of said lever by screws passing therethrough and through lugs 125 on said lever, and the bearing 123 being on a cross-piece 126, which closes the guideway in said lever and is fixed to the body of said lever by screws 127.

10 A block 131 is threaded to said screw and has movement in a guideway 132 extending lengthwise of said lever and said screw, said guideway being exemplified as a dovetailed guideway. The block has a crank-pin 133 thereon.

15 The screw has a bevel-pinion 135 fixed thereto, which is meshed by a bevel-gear 136, fixed to a shaft 137, journaled in a bearing-block 138, fixed to the lever 73 by screws 139, this bearing-block being provided with an annular flange 140, through which said screws pass into a journal-stud 141 on said lever. (See Figs. 9 and 11.) Said journal-stud is journaled in a bearing 142 in the 20 housing, providing pivotal movement for said lever on the housing. The construction holds these journals and bearings in endwise relation.

25 A handle 143 is fixed to said shaft for rotating the bevel-gear 136, and thereby adjusting the articulating pin 133 lengthwise of said lever for adjusting the lengths of feeding movements of the work.

30 Gauging means are provided for gauging said lengths of feeding movements, exemplified as a pinion 146, fixed to the shaft 137, the handle 143 being received about the hub 147 of said pinion. (See Fig. 9). This pinion meshes with a gear 148, journaled on a stud-shaft 149, fixed in the flange 140, and being fast with a pinion 150, which meshes with a gear 151, journaled about the hub 147 of the pinion 146, and in a bearing 152 of a cap 153 of the housing, fixed to 35 the body of said housing by screws 154.

40 An index-plate 158 is fixed to rotate with the hub 159 of said gear 151, as by a key 160. The said gear, the said dial-plate and the handle 143 are held in endwise relation for endwise positioning of the parts, by having suitable shoulders thereon and on the bearing 152, a pin 161 being received through said handle, the hub 147 and the shaft 137.

45 An index-finger 165 is secured to the flange 140, (see Figs. 1, 2 and 8), and projects past said gears through a slot 166 in the cap 153, for registering with the markings 167 on said index-plate. The slot 166 is provided for permitting relative rocking movements between the housing 83 and the lever 73, to which latter said index-finger is secured.

50 The adjusting screw 121 is provided with a collar 170, fixed thereto by a screw 171, and having a locating socket 172, into which

a coacting ball 173, located in a socket 174, of a bracket 175, on the arm 73, is arranged to be received, the ball being urged into said locating socket 172 by means of a spring 176 in said socket 174.

70

The structure and relation of the parts are such that coactive relation between said ball and said socket is obtained at each revolution of the adjusting screw, thereby indicating to the operator who manipulates the handle 143, that a complete revolution of said adjusting screw has been effected, and that consequently an adjustment of distance of feeding movement of the work corresponding to a revolution of the screw has 75 taken place. Thus, if said adjusting screw has a thread of one-half inch lead, a resultant feeding adjustment has been effected.

It may be instanced that the index on the index-plate is divided in graduations representing one hundred and fifty thousandths of an inch in variation of feeding distances between the work and the tool. It may be further instanced that said one hundred and fifty thousandths of an inch, represented on the circumference of the index-plate, are divided into fifteen divisions, each representing ten one-thousandths, indicated by the division lines on said index, and that one revolution of the adjusting screw 121 represents a variation in feeding movements of 80 said ten one-thousandths of an inch.

85 The operator instinctively knows that each time there is coaction between said ball and said socket, which he can feel in turning the screw, he has adjusted the handle 143 the equivalent of ten one-thousandths of an inch variation in the feeding strokes.

90 If, therefore, he is required to make an adjustment representing a number of ten one-thousandths of an inch, he can note the relative position of the index-finger and the index, and quickly mentally calculate the number of ten one-thousandths of an inch it will be necessary for him to pass on 95 the index in order to effect the proper correlation between the index-finger and the index desired, and quickly rotate the adjusting handle accordingly, the said rotations causing coaction between the ball and socket for the equivalent of each ten one-thousandths of movement of the dial, the operator feeling these coactions at the handle, making it unnecessary for him to view the dial during such main adjustments.

100 The ball and socket are provided for the further purpose, that their coaction insures registry between the respective division lines and the index-finger and guards against inaccuracy on the part of the operator in setting the dial. If, for instance, an operator were to set the dial so that the division line does not register with accuracy with the finger, the result might be that the pawl would not pass the desired tooth in 110 115 120 125 130

the ratchet-wheel during feeding, and the feed would be minus the feeding effect of that tooth.

The reciprocating movements of the swinging arm of the lever 73 are translated into rotative intermittent feeding movements of the feed-screw 36.

The feed-screw is provided with an extension 191, the outer end of which is provided with a manual operating part 192, shown as a square end for receiving a suitable wrench for manually rotating the feed-screw. (See Figs. 2 and 3.)

Gears 177, 178, rotate loosely about the feed screw, on a bushing 179 keyed to the feed-screw, and are located in a gear-box 180. (See Figs. 2 and 3.) The gear-box is fixed to the outer end of the rail, as by means of bolts 181, 182, securing the gear-box to a bracket 183, in turn secured to the rail by bolts 184.

The bushing is held endwise between a collar 185 fixed to the feed-screw and a collar 186, a nut 187 clamping the latter collar and the bushing endwise on the feed-screw. The feed-screw is held endwise, as by collars 185, 188, at the respective sides of the bearing 38.

The said gears are held in endwise separated relation on the bushing, for instance, by means of shoulders 189, 190, on the bushing, separating movement of the gears being prevented by the collar 185, and a bearing 193.

A clutch-collar 195 is received about said bushing, and is held to rotate therewith, as by a spline-key and groove-connection 196. Clutches 197, 198, are located between the clutch-collar and said respective gears 177, 178, these clutches being shown as toothed clutches, the teeth whereof are respectively on said clutch-collar and said gears.

The clutch-collar is operated by means of a finger 201, received in an annular groove 202 in said clutch-collar, and fixed to a rack-rod 203, having endwise movement in a bearing 204, of the bracket 183, fixed to the rail 33. (See Fig. 5.) Means are provided for preventing the rack-rod from turning, as by a spline-key and groove connection 205 between it and its bearing.

A pinion 208 is on a shaft 209, and meshes with the rack. This shaft is journaled in a bearing 210 in said bracket. It is provided with an annular groove 211, into which the end of a bolt 212, threaded into said bracket, is received, for holding said shaft endwise.

The shaft is provided with a handle 213 for rotating the same. It is provided with a collar 214, having sockets 215, 216 and 217 therein, into which a plunger 218 is arranged to be selectively received, the plunger being spring-pressed by a spring 219, in a bore 220, in which said plunger operates,

being held therein by a threaded plug 221, threaded into the outer threaded end of said bore. Engagement between the spring-pressed plunger and the intermediate socket maintains the clutch-collar in intermediate or neutral position. The turning of the handle, for engagement of either clutch causes engagement between said spring-pressed plunger and one of the side sockets, for maintaining clutch engagement. 75

A ratchet-wheel 225 is rotatable about a stud-shaft 226, fixed in bearings 227, 228, respectively in said bracket and the gear-housing. (See Figs. 5, 6 and 7.) A gear 229 is fixed to said ratchet-wheel and rotates therewith. 80

A pawl-lever 231 has a bearing 232 about said stud-shaft, and has a pawl 233 pivoted thereabout on a pin 234. (See Figs. 6 and 7.) A spring 235 is fixed to the pawl-lever by a bolt 236 and a pin 237 at one end thereof, and has a pad 238 received against the straight face 239 of the hub of said pawl, for resiliently causing engagement of the tooth-end of said pawl with the teeth of the ratchet-wheel. 90

The gear 229 meshes with a gear 241, which is rigidly connected with a gear 242 by means of a hub 243, the said gears rotating on a stud-shaft 244, in bearings 245 in the gear-casing. (See Figs. 2 and 5.) The gear 229 also meshes with the gear 178 loose about the feed-screw. The gear 242 meshes with the gear 177. In this manner the gears 177, 178, are rotated in opposite directions. 100

The extent and direction of movement of either of said gears 177, 178, is transmitted to the feed-shaft, according to which of the clutches is engaged, and according to the extents of rocking movements of the lever 73. 105

The reciprocating rocking or swinging movements of the lever 73 are transmitted as reciprocating movements to the pawl-lever 231 by means of a link 249, having a bearing 250 about the crank-pin 133 and a bearing 251 about a shoulder-bolt 252 on the pawl-lever, serving as articulations between the ends of said link and the levers 73 and 231 respectively. (See Figs. 6, 9 110 and 10.)

The length of reciprocating movement thus imparted is governed by the adjustment of the crank-pin 133 lengthwise of the lever 73. 120

The lever 73 oscillates about the axis of rotation of the journal-stud 141, which has fixed relation with the housing 83, which in turn is normally held stationary on the frame of the machine. The articulation between the other end of said link and the pawl-lever is, however, movable up and down along the guideway 41, on which the rail 33 is adjusted. The distance between the axis of rotation of the bull-wheel, which 125

is the point for power application for the feeding movements, and the point for power reception for said feeding movements, which may be instanced as the axis of oscillation of the pawl-lever, therefore varies with the adjustment to elevation of the rail.

The distance between the axis of articulation of the lever 73 with the link 249 and the axis of oscillation of the pawl-lever would also vary with the adjustments to elevation of the rail.

These variations would ordinarily result in variations of distances of feeding movement at the various steps of feeding movement.

Such variations in elevation are compensated for and automatic relocation of the path of reciprocation of the lever 73 is provided to compensate for the various positions of the rail, in order that the distances of intermittent feeding movements accomplished by the feed-screw are maintained regardless of the elevation of the rail.

While the present exemplification of my invention permits slight variation in angular arrangements between the link 249 and the levers at its respective ends in the lower range of adjustments of the rail, such variations are small and negligible, especially as such latter adjustments are infrequent. Such variations do not in practice amount to the length of a tooth-space in the ratchet-wheel, and consequently the feed is constant throughout all adjustments of the rail.

Instancing the compensating feature of the invention, a link 256 is provided, which connects with said rail, being articulated on a shoulder-bolt 257, threaded into the bracket 183. (See Figs. 2 and 5.) The other end of the link is articulated on a pin 258, instanced as a bolt, in a bearing 259 on the lever 95.

When the rail 33 is adjusted to a different elevation, causing a difference in distance between the articulating axis of the articulation 133 and the oscillating axis of the pawl-lever, the lever 95 yields to such adjustment, resisted by the spring 101, the direction of such yield depending on whether such adjustment lengthens or shortens the distance between said axes.

If such adjustment takes place while the bull-wheel is at rest, the housing 83 and the lever 73 are in relatively rigid relations, due to relatively fixed relation between the journal 141, the bearings 142 and 91 of the housing, the journal 97 of the lever 95 in the latter, and the non-rotating eccentric 70, its block 71 and the guideway 72 of said lever. This causes yield of the lever 95 to take place with relation to the housing 83, resisted by the spring 101.

A momentary change in position of the pawl-lever also takes place, the pawl moving idle on the ratchet-wheel in retracting di-

rection, if such adjustment of the rail effects an increasing of the distance between said axes, and if said distance is decreased by such adjustment, a slight advancing rotation of the pawl is caused.

When such adjustment of the rail has been effected, and rotation of the bull-wheel is again begun, whereby rotation of the eccentric 70 is again initiated, thereby permitting rocking movement of the housing 83 and the lever 73, the spring 101 causes the housing to again assume its normal position with relation to the lever 95, which is a central position, as shown in Fig. 11.

The radial position of the housing about its stud-journal 79 is changed by such rocking movement, so that said housing, instead of being in normal vertical position, shown in Figs. 11 and 12, will be at an angle to said vertical position, at either side of its normal vertical plane, according to whether said adjustment of the rail has moved said lever 95 to the right or to the left. Such movement may be described as planetary about the axis of the bull-wheel.

Such change of radial position of the housing will also change the normal radial position of the lever 73 so that said lever 73, instead of reciprocating to equal extents at both sides of the vertical plane coincident with its axis of oscillation, as instanced and shown in the drawings, will reciprocate at both sides of a plane at an angle thereto. The lever 73 is instanced as parallel with the housing 83 when the high point of the eccentric 70 is coincident with the right line passing through its axis of rotation and central with said lever 73.

If such adjustment of the rail takes place while the ram is operating, that is to say, while the eccentric 70 is rotating, the position of the housing and of the normal location of the lever 73 will automatically and stepwise follow the movements of the lever 95, induced by the change of adjustment of the rail, for the reason that the rotation of said eccentric will neutralize in stepwise manner what would otherwise be the aforesaid locked relation of said housing and lever 73.

The resistance of the spring 101 is preferably substantially greater than the resistance to feeding movement of the feed-screw, so that the position of the housing is normally stationary and fixedly related to the lever 95 during the usual feeding movements of the lever 73 and of the feed-train and feed-screw.

During yielding movement of the lever 95, incident to the adjustment of the rail 33, the yield takes place about the axis of rotation of the eccentric 70 as a center.

Yielding movements of the housing with relation to the lever 95 are also permitted. If, for instance, there should be an undue ob-

struction to feeding movement of the saddle or of the feed-screw, occasioned for instance by having the saddle reach the end of its possible feeding movement, thereby causing 5 a locking of the feed-screw in the nut of the saddle, or for other cause, and the operation of the machine continues to normally induce still further feeding movements, there will be a yielding movement of the housing 10 about its axis of rotation about the journal-stud 79, due to the fact that in such relation of parts the articulating pin 133 becomes the fulcrum for the lever 73, the eccentric 70 in its rotations causing reciprocating movements of said lever about said fulcrum and carrying the journal 141 on the lever 73 with said lever 73 in its reciprocations.

The said journal being journaled in the bearing 142 in the housing, thereby causes 20 reciprocating movements of said housing about the axis of the bearing 91 thereof, about the journal-stud 79. This causes reciprocations of the walls 116, 117, between which the spring 101 is located, for causing 25 yield of said spring with relation to the lever 95, and preventing breakage of parts, and acting as a safety device for the feeding train.

The change of angular relation of the 30 lever 95 and housing 83, about the axis of rotation of said housing, induced by the adjustment of the rail, also changes the normal angular relation of the pawl-lever, swinging the same about the axis of rotation of the 35 ratchet-wheel, so that the link 249, connecting said lever 73 with said pawl-lever 231, operates in a path substantially the same in angular relation with said levers, in order that the distance of feeding movement imparted at each reciprocation of the lever 73 40 to the feed-screw remains the same.

The effective angle between the link 249 and the lever 73 and between said link and the pawl-lever are substantially maintained 45 throughout the adjustments.

It is of course obvious that changes may be made in the exemplification of my invention which I have preferred to show, without departing from the spirit of my invention 50 within the scope of the appended claims.

Having thus fully described my invention, what I claim as new, and desire to secure by Letters Patent, is:

55 1. In feeding mechanism of the character described, the combination of a feeding assembly comprising a normally stationary member and a movable member and having a point for power reception, power applying means having a point for power application, adjusting means for positioning said feeding assembly whereby the distance between said points is changed, said power applying means including a normally stationary member and a movable member having a recipro-

cating portion, automatically acting resilient yielding means between said last-named members, means connecting said normally stationary members for fixing the distance between them, and connecting means between 70 said movable members for transmitting intermittent movements from said reciprocating portion of said movable member to said first-named movable member.

2. In feeding mechanism of the character 75 described, the combination of a feeding assembly comprising a normally stationary member and a movable member and having a point for power reception, power applying means having a point for power application, said power applying means comprising a normally stationary member and a movable member having a reciprocating portion, said members having a normal relation between them, automatically acting resilient 80 yielding means between said last-named members, means connecting said normally stationary members for fixing the distance between them, connecting means between 85 said movable members for transmitting movements from said reciprocating portion of said movable member to said first-named movable member, and adjusting means for 90 said feeding assembly for qualifying the distance between said points whereby said normally stationary member and said movable member of said power applying means are placed in abnormal relation, said automatically 95 acting resilient yielding means returning said last-named members to substantially 100 normal relation.

3. In feeding mechanism of the character 105 described, the combination of a feeding assembly comprising a normally stationary member and a movable member and having a point for power reception, power applying means having a point for power application, adjusting means for said feeding assembly 110 for qualifying the distance between said points, said power applying means including a normally stationary member and a movable member, automatic resilient yielding means permitting automatic yielding between said last-named members and causing 115 automatic return to substantially normal relation between said last-named members, means connecting said normally stationary members, and connecting means between said movable members.

4. In feeding mechanism of the character 120 described, the combination of a feeding assembly comprising a normally stationary member and a movable member, power applying means, adjusting means for said feeding assembly whereby the relative elevation 125 between said feeding assembly and said power applying means is changed, said power applying means including a normally stationary member, a movable member and an intermediate member, means whereby to in- 130

terpivot said last three members, means permitting automatic yielding at said last-named means, connecting means between said normally stationary members, and connecting means between said movable members.

5. In feeding mechanism of the character described, the combination with a feeding assembly including an adjustable support, a normally stationary member, and a movable feeding member, of power applying means therefor comprising a lever, a support to which said lever is pivoted, a normally stationary member, automatic yielding means between said last-named support and said 10 last-named normally stationary member, connecting means between said normally stationary members, and connecting means between said lever and said movable feeding member.

20. 6. In feeding mechanism of the character described, the combination with a feeding assembly including an adjustable support and a movable feeding member adjustable with said support, of power applying means 25 for said movable feeding member comprising a feeding lever, a positioning part, a pivot for said lever on said positioning part, automatic yielding means for said positioning part whereby to permit yielding of said last-named pivot, and a connection between said lever and said movable feeding member, said connection arranged to serve as a fulcrum for said lever during yielding of said positioning part by yielding in said automatic 30 yielding means.

35. 7. In feeding mechanism of the character described, the combination with a feeding assembly including a movable feeding member, of power applying means therefor comprising a feeding lever having operative connection with said movable feeding member, a yieldable support to which said feeding lever is pivoted, means for oscillating said lever, and automatic yielding means to normally resist yielding of said support, and arranged to permit yielding of said support upon abnormal resistance by said movable feeding member.

40. 8. In feeding mechanism of the character described, the combination with a feeding assembly including a movable feeding member, of power applying means for said movable feeding member comprising a feeding lever, a yieldable support, a pivot thereon for said feeding lever, said feeding lever having operative connection with said movable feeding member, and automatic yielding means for said yieldable support resisting movement of said pivot for said feeding lever during normal feeding strains and permitting movement of said lever on said connection during abnormal feeding strains.

45. 9. In feeding mechanism of the character described, the combination with a feeding assembly including an adjustable support

and a movable feeding member adjustable with said support, of power applying means for said movable feeding member comprising a feeding lever, a positioning part, a pivot for said feeding lever on said positioning part, a pivot for said positioning part, a normally stationary element, a pivot therefor, connecting means between said normally stationary element and said support, automatic yielding means between said positioning part and said normally stationary element, and connecting means between said feeding lever and said movable feeding member comprising a pivot for said feeding lever.

50. 10. In feeding mechanism of the character described, the combination with a feeding assembly including a support and a movable feeding member, and means for adjusting the position of said support, of a power applying means for said movable feeding member comprising a normally stationary lever, a positioning part, a second lever, a fulcrum between said normally stationary lever and said positioning part, a fulcrum between said second-named lever and said 55 positioning part, an operative connection between said second-named lever and said movable feeding member including a fulcrum for said second-named lever, and an operative connection between said support and said normally stationary lever, and constructed and arranged whereby said second-named lever is movable on said second-named fulcrum during normal resistance of said movable feeding member and whereby said 60 second-named lever is movable on said last-named fulcrum during abnormal resistance of said movable feeding member.

55. 11. In feeding mechanism of the character described, the combination with a feeding assembly including a support and a movable feeding member, and means for adjusting the position of said support, of a power applying means for said movable feeding member comprising a normally stationary lever, a positioning part, and a second lever, a fulcrum between said normally stationary lever and said positioning part, an automatic 65 resilient yielding means between said normally stationary lever and said positioning part, a fulcrum between said second-named lever and said positioning part, and an operative connection between said second-named lever and said movable feeding member including a fulcrum for said second-named lever.

60. 12. In feeding mechanism of the character described, the combination with a feeding assembly including an adjustable support and a movable feeding member adjustable with said support, of power applying means for said movable feeding member comprising a feeding lever, a positioning part, a pivot for said lever on said positioning part, a connection between said lever and said 65

movable feeding member, a locating part for said positioning part, a connection between said locating part and said adjustable support, said positioning part having a normal relation to said locating part arranged to be shifted by shifting of said locating part by adjustment of said support, and automatic means between said locating part and said positioning part to automatically restore normal relations between said positioning part and said locating part.

13. In feeding mechanism of the character described, the combination with a feeding assembly including an adjustable support and a movable feeding member adjustable with said support, of power applying means for said movable member comprising a locating part, a connection between said locating part and said support, a positioning part, automatic resilient means operatively disposed between said locating part and said positioning part to maintain normal relations during operation between said positioning part and said locating part, a feeding lever, a pivot for said lever on said positioning part, and a connection between said lever and said movable feeding element.

14. In feeding mechanism of the character described, the combination with a feeding assembly including an adjustable support and a movable feeding member adjustable with said support, of power applying means for said movable feeding member comprising a locating part, connecting means between said locating part and said support for shifting said locating part during adjustments of said support, a positioning part, automatic resilient means between said positioning part and said locating part for causing automatic shifting of said positioning part according to the adjustments of said locating part, a pivot for said lever on said positioning part, and a connection between said lever and said movable feeding member.

15. In feeding mechanism of the character described, the combination with a feeding assembly comprising a normally stationary member and a movable member, and means for adjusting said feeding assembly, of operating means for said movable member comprising an eccentric, a housing pivoted about the axis of rotation of said eccentric, a normally stationary lever pivoted about said axis, automatic resilient means between said housing and said lever, connecting means between said lever and said normally stationary member, a lever pivoted to said housing, said eccentric arranged to operate said last-named lever, and connecting means between said last-named lever and said movable member.

16. In feeding mechanism of the character described, the combination of a feeding assembly including an adjustable support, means for adjusting the position of the same,

said feeding assembly including a normally stationary member and a movable member, and operating means for said feeding assembly comprising an eccentric, a housing pivoted about the axis of rotation of said eccentric, a normally stationary member pivoted about said axis, connecting means between said normally stationary members, yielding means between said housing and said second-named normally stationary member, a lever pivoted to said housing, said eccentric arranged to operate said lever, a connecting member between said lever and said movable member, and adjusting means between said connecting member and said lever.

17. In feeding mechanism of the character described, the combination of a feeding assembly comprising a normally stationary member and a movable member, means for vertically adjusting said feeding assembly, and operating means for said feeding assembly comprising an eccentric, a housing and a normally stationary lever pivoted about the axis of rotation of said eccentric, automatic resilient yielding means between said housing and said lever, connecting means between said lever and said normally stationary member, a lever pivoted to said housing, said eccentric arranged to operate said last-named lever, connecting means between said last-named lever and said movable member, and adjusting means for the latter on said last-named lever, said adjusting means including a rotatable shaft having an axis of rotation coincident with the axis of oscillation of said last-named lever.

18. In a metal shaping machine, the combination of a feeding assembly including a vertically adjustable support, a movable element for imparting steps of feed, and a relatively stationary element; power applying means for said feeding assembly including a relatively stationary element and a relatively movable element, automatic resilient yielding means between said last-named elements, connecting means between said relatively stationary elements, connecting means between said movable elements, adjusting means for adjusting the connection between said last-named connecting means and said second-named movable element including a shaft, gauging means therefor, said adjusting means and gauging means including a coacting gauging plate and an indicating finger constituting a pair of indicating members, and gearing between said shaft and an indicating member of said pair whereby to reduce the speed of said last-named member with relation to said shaft.

19. In a metal shaping machine, the combination of a feeding assembly including a movable feeding element for imparting steps of feed, an operating lever therefor, an adjusting screw on said lever, a nut therefor, said operating lever provided with a crank

- pin movable with said nut and having operative connection with said movable feeding element, a shaft for rotating said screw, a gauge-plate and an indicating finger constituting an indicating couple including an index divided into divisions, an automatically coacting socket-piece and plunger for said screw arranged to coact at the registry between said finger and said divisions in 5 10 said indicating couple, and gearing between said shaft and a movable member of said indicating couple to translate given rotations of said screw into coactive positions at said divisions between said finger and index.
- 15 20. In a metal shaping machine, the combination with a feeding assembly comprising a normally stationary part and a movable feeding member, of means for operating the latter including a housing, a normally stationary lever having connection 20 25 with said normally stationary part, automatic resilient yielding means between said lever and said housing, a crank-lever, a pivot therefor on said housing, an eccentric for 30 35 operating said crank-lever, the axis of rotation of said eccentric and the pivotal axes of said housing and said normally stationary lever being coincident, connecting means between said crank-lever and said movable feeding member, and means for adjusting said connecting means on said crank-lever.
21. In a metal shaping machine, the combination with the frame, the tool-ram, a feeding assembly, and means for elevating the latter, of a shaft having operative connection with said ram for reciprocating the same, an eccentric rotating therewith, a

housing and a relatively stationary lever pivoted about said shaft, automatic resilient yielding means between said housing and 40 said lever, a crank-lever, a pivot therefor on said housing, said eccentric arranged to operate said crank-lever, a crank on said crank-lever, means for adjusting said crank lengthwise of its crank-lever, and connecting means 45 between said crank and said feeding assembly.

22. In a metal shaping machine, the combination with the frame, the tool-ram, a feeding assembly comprising a normally 50 stationary part and a movable feeding member, and means for adjusting the elevation of said feeding assembly, of operating means for said feeding assembly including a housing, a crank-lever pivoted thereon, a normally stationary lever having connection with said normally stationary part, automatic yielding means between said last-named lever and said housing, a crank on 55 60 said crank-lever, means for adjusting said crank lengthwise of its lever, connecting means between said crank and said feeding assembly, an index-plate, an index-finger therefor, an adjusting shaft for said crank, and reducing gearing between said shaft and 65 said index-plate, said index-finger stationary supported on said crank-lever, said housing comprising a cap for said gearing, and said cap provided with an opening through which said index-finger extends to 70 register with said index-plate.

In testimony whereof, I have hereunto signed my name.

AUGUSTUS M. SOSA.
